TOBACCO PIPE

Desmond Beresford Kinahan, London, England

Application May 21, 1934, Serial No. 726,835
In Great Britain January 16, 1934

2 Claims. (Cl. 131—12)

This invention relates to tobacco pipes of the kind comprising an outer bowl, a removable inner bowl and a removable filter or absorbent insert arranged below the inner bowl.

- 5 The objects of the invention are to provide an improved pipe of the above kind which is cool and dry in smoking, with an efficient and easily cleansed filtering arrangement and which in general appearance is neat and attractive.
- 10 According to the invention the inner bowl is provided with a hole or holes at the bottom and is of such a size and shape that a cavity is left between the bottom of the inner bowl and the outer bowl. Arranged in this cavity is a 15 shallow bowl of porous clay or other suitable absorbent or filtering material and the bottom of the inner bowl fits snugly into the mouth of the shallow bowl. Perforations are provided in the sides of the shallow bowl communicating with 20 the aforesaid cavity and the usual stem carrying the detachable mouthpiece of the pipe also opens into said cavity. The arrangement is such that when suction is applied to the mouthpiece the smoke is drawn from the inner bowl, down into 25 the shallow bowl, out through the side perforations in the latter bowl into the cavity and thence straight to the mouthpiece. There is no passage for the smoke above the top edge or rim of the shallow bowl. Preferably a small cavity is left 30 between the bottom of the shallow bowl and the outer bowl to act as a moisture trap.

To enable the invention to be fully understood it will now be described by reference to the accompanying drawing in which:—

- 35 Fig. 1 is a sectional elevation of a tobacco pipe constructed according to one form of the invention.

Fig. 2 is a plan view with the inner bowl and filter removed.

- 40 Fig. 3 is a sectional elevation of the outer bowl; Fig. 4 is a plan view and

Fig. 5 is a side elevation of the filter bowl.

- As shown the outer bowl 1 is of light construction and is formed with internal projecting ribs 45 2 to form a support for the inner bowl 3 and also for strengthening purposes. The inner bowl 3 which may be of meerschaum, clay or the like has a flange 4 and is carried in a ring 5 having a screwed portion which screws into a threaded seat 6 formed at the top of the outer bowl. This seat may include a cork or other washer 7 to ensure a tight joint. The bowl 3 is supported by its flange 4 on the ends of the ribs 2 and is held in position by the ring 5 as shown.

- 55 The inner bowl 3 is preferably downwardly

tapered and provided with a single central hole 8 at the bottom. The shallow filter bowl 9 is adapted to fit into the cavity between the inner and outer bowls and fits snugly against the inner sides of the outer bowl. Notches 10 are formed in the rim to accommodate the ribs in the outer bowl.

5 The bottom of the outer bowl is preferably formed with a centering projection 11 on which the filter bowl 9 rests and the latter may have a 10 slight recess on the bottom to fit over the projection 11.

The filter bowl 9 is provided with perforations 12 below the rim preferably extending round a portion only of the bowl on the side farthest 15 away from the mouthpiece or stem 13. The pipe stem 13 opens into the cavity containing the bowl 9 and may be provided with a cork or other lining 14 to receive the usual detachable portion of the 20 mouthpiece. The filter bowl may have any desired number of perforations arranged at any 25 desired points.

The outer bowl and stem may be of the substance known under the registered trade-mark "Bakelite" or of wood or any other suitable material.

I claim:—

1. A tobacco pipe comprising in combination an outer bowl having internal ribs, an inner bowl having a hole in the bottom and a flange adapted 30 to seat on the tops of the internal ribs to support the inner bowl within the outer bowl leaving a cavity at the bottom between the two bowls, a perforated filter bowl in said cavity, the lower end of the inner bowl fitting into the mouth of the 35 filter bowl and a mouthpiece attached to the outer bowl and communicating with the cavity containing the filter bowl.

2. A tobacco pipe comprising in combination, an outer bowl having internal ribs, an inner bowl 40 having a hole in the bottom and a flange adapted to seat on the tops of the internal ribs to support the inner bowl within the outer bowl, leaving a cavity at the bottom between the two bowls, said outer bowl having an internally threaded portion 45 above the ribs, a threaded ring adapted to surround the inner bowl and to screw into the threads on the outer bowl to hold the inner bowl in position, a perforated filter bowl in the cavity the end of the inner bowl fitting into the mouth 50 of the filter bowl and a mouthpiece attached to the outer bowl and communicating with the cavity containing the filter bowl.
